COMBINED LIQUID DISPENSER AND BRACKET

Ronald D. Kulhanjian, Oradell, N.J.
(226 Prospect Ave., Hackensack, N.J. 07601)

Filed July 12, 1974, Ser. No. 488,159

Term of patent 14 years

Int. Cl. D23—02

U.S. Cl. D6—95

FIG. 1

FIG. 4

FIG. 2

FIG. 3

FIG. 1 is a perspective view of a combined liquid dispenser and bracket showing my new design.

FIG. 2 is a top plan view thereof with the bracket omitted for ease of illustration.

FIG. 3 is a rear elevational view thereof with the bracket omitted for ease of illustration.

FIG. 4 is a perspective view of the bracket with the dispenser omitted for the purpose of illustrating the configuration of the bracket only.

I claim:

The ornamental design for a combined liquid dispenser and bracket, substantially as shown and described.
